US00D930571S

(12) **United States Design Patent** (10) Patent No.: **US D930,571 S**
(45) Date of Patent: **** Sep. 14, 2021**

(54) **SOLAR ENERGY STORAGE DEVICE**

(71) Applicant: **ALLPOWERS INDUSTRIAL INTERNATIONAL LTD.**, Guangzhou (CN)

(72) Inventor: **Xiaojun Zhong**, Guangzhou (CN)

(73) Assignee: **ALLPOWERS INDUSTRIAL INTERNATIONAL, LTD.**, Guangzhou (CN)

(**) Term: **15 Years**

(21) Appl. No.: **29/722,043**

(22) Filed: **Jan. 24, 2020**

(51) LOC (13) Cl. **13-02**

(52) U.S. Cl.

USPC **D13/102**; D13/107

(58) Field of Classification Search

USPC D13/103, 199, 107, 108, 110, 184, 102,

D13/104, 105, 106, 118, 119, 123, 133;

(57) **CLAIM**

The ornamental design for a solar energy storage device, as shown and described.

DESCRIPTION

FIG. 1 is a front, right side, top perspective view of a solar energy storage device showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines depict portions of the solar energy storage device that form no part of the claimed design.

1 Claim, 8 Drawing Sheets
